UNITED STATES PATENT OFFICE.

HARVEY W. BELL, OF YONKERS, NEW YORK.

STEAM-GENERATING PLANT.

Application filed April 7, 1919. Serial No. 288,068.

To all whom it may concern:

Be it known that I, HARVEY W. BELL, a citizen of the United States, and a resident of Yonkers, Westchester County, and State 5 of New York, have invented certain new and useful Improvements in Steam-Generating Plants, of which the following is a specification, reference being had to the accompanying drawings, forming a part thereof.

10 My invention relates to improvements in heat generating plants and its object is to provide a simple and efficient system for generating steam mechanically. More specifically its object is to provide a system for 15 utilizing both the heat and the kinetic energy developed by an internal combustion engine. A still further object is to provide a combined mechanical steam generating and translating system.

20 These and other objects will appear in the following specification in which the invention will be described and the novel features thereof set forth in appended claims.

The drawing is a diagrammatic representation of a combined steam generating 25 and motor system which is made according to and embodies my invention, the exhaust manifold of the motor being broken away to show the heat exchanger therein and the 30 mechanical heat generator being shown in section. In the drawing 10 designates an internal combustion engine and 11 its shaft. 12 is the engine exhaust pipe which leads from a jacketed manifold 13. The cylinders 35 of the engine are water-jacketed and the intake to the cylinder jacket is shown at 14 and its outlet at 15. 16 is a fuel tank from which is a pipe 17 which leads to the carburettor shown in detached view at 18. A 40 part of this fuel pipe is shown coiled around the exhaust pipe 12 at 19.

20 is a water tank with which the cylinder jacket intake and outlet pipes 14 and 15 are connected, and 21 a discharge pipe therefrom. A pump 22 connected to be driven 45 from the engine 10 by mechanism not shown is arranged to force water from the tank 20 through a check valve 23 into a mechanical heat generator 30. This is preferably a 50 mechanism like that disclosed in my co-pending application for patent Serial No. 279,923, filed February 28, 1919. This comprises a casing 31 within which are disks 32

on the engine shaft 11, between which disks are stationary annular plates 33. Fluid is 55 led into the casing at 34 and discharged therefrom at 35. A pipe 36 leads from this discharge to the exhaust manifold 13. 37 is a pipe leading from the exhaust manifold through a manually controlled valve 38 to a 60 steam motor 40. 39 is a steam dome connected with pipe 37.

The exhaust from the steam motor is carried by a pipe 41 to the upper part of a radiator or condenser 42. Back of this is a fan 65 43 connected to be driven by the engine 10. A pipe 44 leads from the lower part of the condenser to an injector 45, with which the engine exhaust pipe 12 is also connected, and a pipe 46 connects the injector with the 70 water tank 20. A baffle plate 24 is in the water tank above which is the exhaust stack 25.

50 is an automatic regulator for controlling the supply of fluid to the heater 30. It 75 comprises a valve 51 which controls a bypass from pipe 21 through pipe 52, valve 51 and pipe 53 into the water-tank 20. This valve is closed by a small plunger 54 on the end of a hollow expansion tube 55. 56 is a 80 pipe from the casing 31 of the heater at the desired water level therein which communicates with the expansion tube 55.

60 is an adjustable pressure valve connected by a pipe 61 with the pipe 36. This 85 is connected by a rod 62 with a throttle valve 63 between the carburettor 18 and the intake manifold 64 of the engine 10.

The operation of this apparatus is as follows: The engine 10 is operated in the usual 90 manner and its operation generates heat in the cylinders some of which is absorbed in the water jacket and heats the water in the tank 20 with which the cylinder jacket is connected by a thermal siphon through the 95 pipes 14 and 15. Some of the heat is absorbed in the exhaust manifold by the fluid which enters by pipe 36 and leaves by pipe 37, and some of the heat remains in the exhaust gases which pass through pipe 12, 100 through the injector 45 and by pipe 46 into tank 20 into which they are deflected downwardly by the baffle plate 24 and further heat the water in the tank before they pass out through the stack 25.

105 The heat of the exhaust pipe 12 may be

utilized to raise the temperature of the fuel in the coil 19 before it reaches the carburetor.

The operation of the engine results in rotating its shaft 11 by which the disks 32 of the heat generator 30 are driven, either by being directly mounted on the shaft as shown, or geared to be rotated at a comparatively higher speed. The water from the tank 20 is forced by the pump 22 to the generator 30 and heated therein. From the generator 30 it is led in the form of steam by the pipe 36 to the exhaust manifold where it is superheated. Thence it goes through pipe 37 and valve 38 to the motor 40 where it is transformed into useful work.

The exhaust steam then goes through pipe 41 to the condenser 42 where it is cooled. The fan 43 circulates air through the condenser. The condensed water is then passed through pipe 44 into the injector 45 where the exhaust gases heat it and force it through pipe 46 back into the tank 20, where it is further heated by the exhaust gases.

The regulator 50 maintains the desired water level in the generator 30 in the following manner. When the annulus of rotating water in the generator is large enough to cover the outlet to pipe 56, water will be led into the expansion tube 55. When water is in this tube its length will be short enough to remove the plug 54 from the valve seat and the water from pump 22 will circulate through the by-pass formed by the pipes 52 and 53 back into the tank. The heat generator 30 evaporates the water in the casing 31 and as soon as the amount of this water decreases enough to uncover the outlet to pipe 56, steam will be led into the expansion tube 55. This results in raising the temperature of the tube and increasing its length enough to close plug 54 against the valve seat to close the by-pass. Then the water from pump 22 will be forced through check-valve 23 into casing 31 through the inlet 34 until enough water is admitted to cover the outlet to pipe 56. Then the expansion tube will be cooled and will again open the by-pass.

The steam motor is controlled by the valve 38. When the valve 38 is closed or when steam is generated more rapidly than it is used, its pressure will rise and the pressure regulator 60 will close the throttle valve 63 to slow down the engine 10. The steam dome 39 is provided for the purpose of accumulating surplus steam.

The sequence of passing the fluid through the various parts which combine to raise its temperature is not material. Neither is it necessary that the fluid be passed through every one of the temperature raising parts of the apparatus to come within the scope and spirit of this invention. The invention upon which this application is based is

broader than the arrangement which is shown diagrammatically in order to illustrate one of the ways in which it may be used and I intend no limitations other than those imposed by the appended claims.

What I claim is:

1. An internal combustion engine having a cooling jacket, a mechanical heat generator connected to be driven by the engine, and means for successively passing a fluid through the jacket and generator in desired sequence, to thereby cumulatively heat the fluid by both the mechanical heat generator and the internal combustion engine which drives the same. 70

2. An internal combustion engine having a cylinder jacket and an exhaust manifold jacket, a mechanical heat generator connected to be driven by the engine, and means for successively passing a fluid through both of said jackets and the generator in desired sequence, to thereby cumulatively heat the fluid by both the mechanical heat generator and the internal combustion engine which drives the same. 75 80

3. An internal combustion engine having a cylinder jacket and an exhaust manifold jacket, means for subjecting the fluid from both said jackets to the exhaust gases from the engine, a mechanical heat generator connected to be driven by the engine, and means for successively passing a fluid through both of said jackets, and means for subjecting said fluid to the exhaust gases and the generator in desired sequence. 95 90

4. An internal combustion engine having a cylinder jacket and an exhaust manifold jacket, an injector wherein the fluid from said jackets is brought in contact with the exhaust gases from the engine, a fluid tank, means for leading said gases into the water tank, a mechanical heat generator connected to be driven by the engine, and means for successively passing a fluid through both of said jackets, the injector, the tank and the generator in desired sequence. 100 105

5. An internal combustion engine having a cylinder jacket, and an exhaust manifold jacket, an injector wherein the fluid from said jackets is brought in contact with the exhaust gases from the engine, a fluid tank, a fluid circulating pump and connections whereby a fluid is successively passed through both of said jackets, the injector, the tank and the generator in desired sequence. 110 115 120

6. An internal combustion engine, having a cooling jacket, a fluid tank, a mechanical heat generator connected to be driven by the engine, a circulating pump and connections whereby a fluid is successively passed through the jacket and generator, a by-pass around the generator and automatic means for controlling the by-pass. 125

7. An internal combustion engine having 130

- 5 a cooling jacket, a mechanical heat generator directly operated by said engine, means for successively passing a fluid through the jacket and generator in desired sequence to cumulatively utilize the heat of both the mechanical heat generator and the internal combustion engine to produce a pressure fluid and a fluid pressure motor connected to be directly operated by said pressure fluid.
- 10 8. An internal combustion engine, a mechanical heat generator connected to be driven by the engine, a translating device arranged to utilize the heat produced by the combustion engine and by said generator.
- 15 9. An internal combustion engine, a mechanical heat generator connected to be driven by the engine, a translating device arranged to utilize the heat produced by the combustion engine and by said generator and manual means for controlling said translating device.
- 20 10. An internal combustion engine, a mechanical heat generator connected to be driven by the engine, a translating device arranged to utilize the heat produced by the combustion engine and by said generator and means automatically actuated by the generated heat for controlling the speed of the engine.
- 25 11. An internal combustion engine, a mechanical heat generator connected to be driven by the engine, a translating device arranged to utilize the heat produced by the combustion engine and by said generator, manual means for controlling said translating device and means automatically actuated by the generated heat for controlling the speed of the engine.
- 30 12. An internal combustion engine, a mechanical heat generator connected to be driven by the engine, means for utilizing the heat of combustion and said generator for heating a fluid to produce pressure, and a fluid pressure motor arranged to be actuated by said heated fluid.
- 35 13. An internal combustion engine, a mechanical heat generator connected to be driven by the engine, means for utilizing the heat of combustion and said generator for heating a fluid to produce pressure, a fluid pressure motor, fluid connections between the engine, generator and motor, and a manually actuated control valve for the motor in said connections.
- 40 14. An internal combustion engine, a mechanical heat generator connected to be driven by the engine, means for utilizing the heat of combustion and said generator for heating a fluid to produce pressure, a fluid pressure motor, a condenser, fluid connections from the engine and generator to the motor and other fluid connections including the condenser from the motor to the engine and generator.
- 45 15. An internal combustion engine, a mechanical heat generator connected to be driven by the engine, means for utilizing the heat of combustion and said generator for heating a fluid to produce pressure, a fluid pressure motor, a condenser, fluid connections from the engine and generator to the motor and a manually actuated control valve for the motor in said connections.
- 50 16. An internal combustion engine, a mechanical heat generator connected to be driven by the engine, means for utilizing the heat of combustion and said generator for heating a fluid to produce pressure, a fluid pressure, a condenser, fluid connections from the engine and generator to the motor, a manually actuated control valve for the motor and an automatically actuated control valve for the engine in said connections.
- 55 17. An internal combustion engine having a cooling system, a mechanical heat generator driven by said engine, a fluid pressure motor, connections for supplying fluid heated by the cooling system of the internal combustion engine and the mechanical heat generator to said fluid pressure motor and connections from the fluid pressure motor for returning the exhaust fluid therefrom back to take up heat from the cooling system of the internal combustion engine.
- 60 18. An internal combustion engine, a mechanical heat generator driven thereby, a translating device arranged to utilize the heat produced by the combustion engine and by said generator and means automatically actuated by the generated heat for controlling the power output of the engine.
- 65 19. An internal combustion engine, a mechanical heat generator driven thereby, a translating device arranged to utilize the heat produced by the combustion engine and by said generator, manual means for controlling the translating device and means for automatically governing the power output of the internal combustion engine in accordance with the utilization of the generated heat by the translating device.
- 70 In witness whereof, I have hereunto set my hand this 5th day of April, 1919.
- HARVEY W. BELL.
